Inventor:

Andrew C. Wood,

By Shee Shee My 3

UNITED STATES PATENT OFFICE.

ANDREW C. WOOD, OF CHICAGO, ILLINOIS.

MOTOMETER.

Application filed July 29, 1921. Serial No. 488,434.

To all whom it may concern:

Be it known that I, ANDREW C. WOOD, a citizen of the United States, residing at Chicago, in the county of Cook and State of Illinois, have invented certain new and useful Improvements in Motometers, of which the following is a description.

My invention relates to improvements in motometers and more particularly to a motometer which may be illuminated so that the thermometer may be observed and read in the dark as well as in the light. Among the other objects of my invention I have sought to provide a device of the kind described which is simple, convenient, compact, economical, attractive, durable, and efficient and satisfactory for use wherever found applicable. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts;

Figure 1 is an elevation of my invention as applied to a radiator cap, viewed from the driver's seat;

Figure 2 is a side elevation thereof;

Figure 3 is an elevation similar to that shown in Figure 1, viewed from the front of the vehicle;

Figure 4 is a sectional view taken substantially on the line 4-4 of Figure 1;

Figure 5 is a sectional view taken substantially on the line 5-5 of Figure 1 parts being broken away;

Figure 6 is a view similar to that shown in Figure 1 and represents a modified form of the device; and

Figure 7 is a sectional view taken substantially on the line 7-7 of Figure 6.

In the drawings wherein I have illustrated the preferred embodiment of my invention, 1 represents a radiator cap, to which the motometer 2 is secured, said motometer being of any desired shape and material and comprising a chambered casing having opposed front and rear walls, 3 and 4 respectively, said walls having central openings 5 therein preferably adapted to receive lenses, covers or glasses 6 and 6' therein.

Extending vertically in the chamber of the motometer casing, substantially centrally thereof, is a thermometer stem 7, and to one side thereof, that is, to the front of the stem, as shown in the drawings, is arranged a dial or partition 8, said dial being generally of an opaque material and having markings thereon (not shown) for indicating the temperature, proportional to the height of the indicating fluid in the thermometer stem. A circle 9 may be imprinted on the face of the dial, as shown in Figure 1, at any desired portion thereof relative to a certain predetermined temperature point recorded by the thermometer stem, or hole provided.

One or more lamp housings 10, as shown, preferably, but not necessarily integral with the casing 2 are arranged at the periphery of the casing and extending preferably transversely thereto, that is, the axis of the lamp housings shown extend from the front toward the rear of the casing. The housing 10 is open at both ends thereof, the forward end being adapted to receive a lens 11 whereby the light from within may be projected forward of the motor vehicle, said housing being of any desired shape. The rear end of said housing is threaded so as to receive a closure plug 12, said closure plug having a lamp socket 13 inwardly thereof and having a terminal contact 14 adapted to engage the cooperating base contact of the lamp 15, there being a lead wire 16 connected to said socket. The lead wire 16 is preferably arranged within the casing 2 and extends therefrom at the base so that it may be detachably connected as at 17 to any suitable source of electrical energy, such as a storage battery, generator, or the like.

The housing 10 is so formed that it has an opening 18 therethrough in the wall thereof communicating with the interior of the casing 2, as shown in Figure 4, so that a portion of the light from said lamp 15 will be directed downwardly between the opaque partition 8 and the thermometer stem 7 in order to illuminate said stem so that it can be read from the driver's seat at night as well as in the day time. One of the covers, 105 as for instance 6', may be opaque and of sheet metal stamping, or it may be of a transparent or translucent material and have any suitable or preferred emblem or design 19 thereon, it being illuminated from behind, as shown in Figure 4, when the lamp is lighted. If desired, a partition 8" of any

suitable material having a photograph, emblem or design thereon may be arranged, as shown, or a transparent design sheet mounted immediately behind the lens 6'.

5 In the modifications shown in Figures 6 and 7 the transverse lamp housing 10 is dispensed with and a pair of lamps 21 are arranged in the casing 2' on opposite sides of the thermometer stem 7. In this modification the opaque dial or partition 8' extends from one side to the other of the casing, adjacent the rear side thereof against the glass or cover 6, said partition forming a boxlike or looped structure about the stem 7 open at 10 only one side thereof, as at 22. In the opposite walls of the partition 8' are formed one or more apertures 23 in registry with the thermometer stem so that light from the lamps 21 may pass through said apertures 15 and onto said stem, whereby said thermometer may be read from the driver's seat. It will be observed in this modification that the cover plate 6' is illuminated directly by the lamps 21.

25 What I claim as new and desire to secure by Letters Patent is:

1. In a device of the kind described and in combination, a motometer comprising a casing having a thermometer stem therein, 30 a vertical partition substantially enclosing said stem and extending to one side thereof, said stem enclosing portion of the partition having an aperture therethrough, said casing having openings in the opposite 35 faces thereof to receive covers therein, a housing at the upper end of said casing having an opening communicating with the interior of said casing, said housing being open at its ends, a lens arranged in one of 40 the open ends of said housing, detachable closure means for the other ends of said housing, and a lamp removably positioned within said housing whereby said lamp may be illuminated so that the light therefrom is 45 directed through said communicating openings into said casing compartments so as to illuminate said stem.

2. In a device of the kind described and in combination, a casing having openings 50 at the sides thereof, covers for said openings, partitions in said casing vertically thereof and parallel to said covers dividing said casing into separate compartments, a lamp housing adjacent the periphery of said casing and opening into said compartments, a lens on one end of said housing away from said opening, a lamp at the other end of said housing, the filament thereof being located opposite said opening into said compartments, and means for energizing said lamp to illuminate said compartments.

3. In a device of the kind described and in combination, a motometer comprising a casing having a thermometer stem therein, 55 a vertical partition in said casing and sub-

stantially enclosing said stem and having an aperture therethrough opening onto said stem, a housing at the upper end of said casing having an opening communicating with the interior of the casing, and a lamp within said housing, whereby light therefrom will illuminate said stem.

4. In a device of the kind described and in combination, a motometer comprising a casing having a thermometer stem arranged 75 therein, a vertical partition substantially enclosing said stem and provided with an aperture through that portion adjacent the stem, a housing at the upper end of said casing and having an opening communicating 80 with the interior of the casing, said housing open at its ends, a lens arranged in one of the open ends of said housing, detachable closure means for the other end of said housing, and a lamp within said housing, whereby the light therefrom will be directed through said communicating openings to illuminate said stem.

5. In a device of the kind described and in combination, a motometer comprising a 90 chambered casing, a thermometer stem arranged vertically therein, an opaque vertical partition arranged transversely within the casing, about said stem and having an aperture through its stem-enclosing portion, 95 a lamp housing at the top of said casing and having an aperture therethrough communicating with the interior of the casing, whereby light from within said housing will be directed through the casing to illuminate 100 said stem.

6. In a device of the kind described and in combination, a casing having means for mounting the same to a cooperating structure, transparent covers for the sides of said casing, an opaque partition in said casing parallel with and intermediate said covers, a partition in said casing parallel with said opaque partition and adapted to have a design thereon, a lamp housing adjacent the periphery of said casing and opening into the compartment between said partitions, a lamp in said housing, and means for energizing said lamp to illuminate said compartment and the design on said second-mentioned partition.

7. In a device of the kind described and in combination, a motometer comprising a casing having openings at the sides thereof, covers for said openings, a thermometer 120 stem in said casing, partitions in said casing vertically thereof parallel to said covers, substantially enclosing said stem and dividing said casing into separate compartments, a lamp housing on the periphery of said casing at one side and opening into said compartments, a lens on one end of said housing, a lamp at the other end of said housing and having its filament located opposite the opening into said compartments, and means 125 130

for energizing said lamps to illuminate said stem.

8. In a device of the kind described and in combination, a motometer comprising a casing having a thermometer stem therein, partitions in said casing vertically thereof and substantially enclosing said stem and dividing said casing into separate compartments, a plurality of lamp housings about 5 the periphery of said casing and opening into said compartments, a lens on one end of each of said housings, a lamp at the other 10

end of each housing and having its filament located opposite the opening into said compartments, and means for energizing said 15 lamps to illuminate said compartments.

In testimony whereof, I have hereunto signed my name in the presence of two subscribing witnesses.

ANDREW C. WOOD.
